UNITED STATES PATENT OFFICE.

CHARLES G. SMITH, OF MEDFORD, MASSACHUSETTS, ASSIGNOR, BY MESNE ASSIGNMENTS, TO RAYTHEON INC., OF CAMBRIDGE, MASSACHUSETTS, A CORPORATION OF MASSACHUSETTS.

ELECTRICAL APPARATUS.

Application filed July 30, 1923. Serial No. 654,644.

The present invention relates to electrical apparatus and more particularly to the type of electrical apparatus disclosed in the patents to Smith No. 1,545,207 July 7, 1925, and 5 1,617,171 February 8, 1927.

The basic invention disclosed in the first of the above mentioned applications consists of a novel type of insulating device having electrodes immersed in a gas and spaced 10 apart a distance which is so short that gaseous ionization is normally impossible even under the influence of high electrical potentials. Such a device is insulating because electrons traversing the gaseous medium 15 under the action of an electric field are not allowed to collide with a sufficient number of molecules to initiate cumulative ionization and consequent conduction. However, as is disclosed in the second of the above mentioned applications, it has been found that such apparatus may be made conducting by causing electrons to take long paths through the gaseous region included between the electrodes. The specific form of the apparatus illustrated and described in the above 20 application employs a magnetic field for deflecting the electrons in a direction transverse to their normal direction in such a manner as to lengthen their paths in the gas, 25 thereby allowing more frequent collisions with gas molecules.

The principal object of the present invention is to provide improvements in apparatus of this general nature whereby the 30 gaseous conduction may be controlled.

With this object in view, I have discovered in connection with such conducting devices that the intensity of electrical conduction depends materially upon the continuity of 40 the ionization throughout the entire gaseous region and that if the means employed for lengthening the electron paths is partially or wholly suppressed over a small portion of the region, the conducting properties of the 45 apparatus as a whole may be greatly altered. Accordingly, the present invention contemplates the provision of means for deflecting electrons and lengthening their paths in a gaseous region which is of sufficiently restricted dimensions to normally prevent ionization, together with means for altering the path lengthening means over a small 50 portion of the region.

It has been found in connection with ap-

paratus of this type that if the ionization is 55 distorted or suppressed over a sufficiently large portion of the gaseous region, the conducting properties of the apparatus as a whole may be practically reduced to zero. However, the principal advantages of this 60 invention reside in the fact that the conductivity of the gas may be caused to vary in step with any variations in the value of the path lengthening means, thus allowing the apparatus to be conveniently used for 65 amplifying, generating or otherwise operating upon electrical oscillations.

The operation of this device may be briefly explained as follows: Conduction between electrodes in a gas subjected to a potential 70 difference is believed to be caused by the collisions of electrons against gas molecules to ionize the molecules. The collision of an electron having sufficiently high velocity against a gas molecule tends to form from 75 the molecule a positive ion and another electron. The electrons and ions so formed, together with the original electrons are in themselves free to collide with other molecules and ions. The conducting condition of 80 a gaseous conducting device depends upon the cumulative effect of the ionization caused by a number of such collisions. In the present invention, an electron originally impelled directly between the electrodes is deflected 85 by the path lengthening means so that its first collision with a gas molecule takes place at a considerable distance from the original position of the electron. The ions and electrons so formed are in themselves able to introduce 90 more ions and electrons into the gas either by bombardment of the electrodes or by collision with other gas molecules. The electrons are in turn deflected by the path lengthening means and cause further collisions at 95 points removed from the first collision. It will thus be seen that the action is progressive and that if conditions are uniform over the entire electrode surfaces, the necessary conditions for cumulative ionization will be 100 fulfilled and conduction will take place. However, if one or more of the collisions occur in a region where the path lengthening means is considerably suppressed, the electrons so formed will be impelled directly between the electrodes and will be unable to 105 ionize other gas molecules. The cumulative ionizing action is thus forestalled and if the

distortion is caused to take place over a sufficiently large area, gaseous conduction in the entire region may be suppressed. Furthermore, if the path lengthening means be allowed to fluctuate about a certain average value, the conductivity of the gaseous medium will be caused to vary in step with the fluctuations in the path lengthening means, thus allowing the apparatus to be used as a device for operating upon electrical oscillations.

In the drawings illustrating the preferred form of the invention, Figure 1 is an elevation in section of an apparatus embodying the features of the present invention; Fig. 2 is a section on line 2-2 of Fig. 1; and Fig. 3 is a diagram of a simple amplifying circuit embodying one of the devices shown in Fig. 1.

The illustrated embodiment of the invention employs a pair of electrodes preferably having plane opposing surfaces mounted within an insulating receptacle. The distance between the electrodes is short and comparable to the mean free path of electrons in the gas, that is so short that electrons traveling directly across the gas space between the electrodes produce insufficient ionization to initiate substantial conduction. (The mean free path of electrons, as herein connoted, is the average distance traveled by the electrons without ionizing impact with gas molecules or atoms.) Conduction is caused to take place by means of a magnetic field impressed in the gaseous region by suitable magnetic poles. An auxiliary pole is provided for the purpose of distorting the magnetic field over a small portion of the gaseous region. The magnetization of the auxiliary pole may be caused to vary by any suitable means, thereby varying the conductivity of the entire gaseous medium included between the main electrodes.

As shown in Figs. 1 and 2, the glass receptacle 10 is provided with a reentrant stem 16 upon which are supported two annular electrodes 11 and 12 having plane surfaces spaced a distance apart which is short and comparable to the mean free path of electrons in the gas. The electrode 11 is supported upon stem 16 by means of metallic straps 15 and electrode 12 is conveniently supported upon a restriction 17 of the stem. Both electrodes are so spaced within the receptacle that all points are sufficiently close to the walls of the receptacle and stem so that ionization adjacent the insulating parts of the apparatus is normally impossible. Suitable lead wires 11' and 12' are sealed into the receptacle and are attached to electrodes 11 and 12, respectively. For the purpose of lengthening the electron paths, two magnetic poles 4 and 5 are provided. The pole 4 is adapted to fit concentrically in the reentrant stem and pole 5 is annular in form and surrounds the receptacle 10. Poles 4 and 5 are

magnetically energized by means of a permanent magnet 6. Pole 5 is not in the form of a complete ring but has a portion broken away into which fits the auxiliary pole 8, as shown in Fig. 2. The auxiliary pole 8 is magnetized by a coil 18 wound thereon. The operation of the apparatus is determined by the magnitude of the auxiliary pole 8, as well as by the spacing of the electrodes and by the strength of the permanent magnet 6. It has been found that in the usual construction of apparatus of this type, the pole 8 may be conveniently made so as to subtend an angle of approximately $22\frac{1}{2}$ degrees, that is, one-sixteenth of the circumference.

The operation of this apparatus has been previously explained. From this explanation, it will be seen that if the auxiliary pole 8 is maintained at a zero value of magnetization, the ionization will be distorted in such a manner that the conductivity of the gaseous region as a whole will be greatly reduced and may, under certain conditions, be made practically zero. It has been found that for certain values of magnetization of pole 8 between zero and that of pole 5, the conductivity of the gaseous region is extremely sensitive to variations in magnetization of pole 8. An amplifying system embodying one of these devices is shown diagrammatically in Fig. 3. This circuit comprises an input circuit 28 upon which the oscillations to be amplified are impressed and an output circuit 29 containing a source of direct current energy. The received oscillations which are impressed at 20 are transmitted to the input circuit 28 through a transformer 25. The input circuit 28 includes the coil 18 upon the pole 8. A condenser 27 is included in the circuit for the purpose of tuning the circuit to the frequency of the oscillations. The output circuit 29 includes electrodes 11 and 12, together with a source of direct current energy 22. The main magnetic means for lengthening the electron paths is indicated generally at 6. As previously stated, it is usually desirable to have the auxiliary magnetic pole operating about some average value of magnetization between zero and that of pole 5. To this end, the input circuit 28 preferably includes a source of direct current energy 23. For the utilization of the amplified oscillations, the output circuit 29 may be conveniently connected to a third circuit 35 by means of a transformer 30. The amplifying action takes place through the distortion of the cumulative ionization and conduction of the gaseous region between the electrodes because of the variations in magnetization of the auxiliary pole 8 caused by the incoming oscillations.

While it is preferred to employ the specific construction and arrangement of parts shown and described, it will be understood that this construction and arrangement is not essen-

tial except so far as specified in the claims and may be changed or modified without departing from the broader features of the invention.

- 5 The invention having been described, what is claimed is:
1. An electrical apparatus comprising two electrodes immersed in a gas, the distance between the electrodes being comparable to the 10 mean free path of electrons in the gas, means for lengthening the electron paths in a direction parallel to the electrode surfaces, and means for altering the effect of the path lengthening means over a restricted portion 15 of the gaseous region between the electrodes.
  2. An electrical apparatus comprising a gaseous region and having one dimension so small that gaseous ionization under the action of an electric field coincident in direction with 20 the small dimension is impossible, means for deflecting electrons and lengthening their paths in the gas, and means for distorting the effect of the path lengthening means over a restricted portion of said gaseous region.
  - 25 3. An apparatus for operating upon electrical oscillations comprising electrodes adapted to be oppositely charged immersed in a gas and spaced apart a distance comparable to the value of the mean free path of elec-

trons in the gas, a pair of cooperating magnetic poles for the purpose of impressing a magnetic field in the region between the electrodes, an auxiliary magnetic pole adapted to be varied by oscillations to vary the magnetization of the auxiliary pole to alter the 30 magnetic field over a portion of the gaseous region and vary the conductivity of the region as a whole in accordance with the received oscillations.

4. An apparatus for operating upon electrical oscillations comprising a gas filled receptacle, a pair of electrodes spaced therein a distance comparable to the value of the mean free path of electrons in the gas, and adapted to be excited by an electrical potential difference, a pair of cooperating magnetic poles adapted to impress upon the gaseous region a magnetic field parallel to the electrode surfaces, an auxiliary magnetic pole for the purpose of distorting the magnetic 40 field over a portion of the gaseous region between the electrodes, and a coil wound upon the auxiliary pole and adapted to be excited by the oscillations in a manner to vary the conductivity of the gaseous region in accordance 45 therewith.

CHARLES G. SMITH.
